UNITED STATES PATENT OFFICE.

ROBERT CHARLES COLE, OF HARTFORD, CONNECTICUT, ASSIGNOR TO JOHNS-PRATT COMPANY, OF HARTFORD, CONNECTICUT, A CORPORATION OF CONNECTICUT.

MANUFACTURE OF INCLOSED FUSES.

No. 866,716.

Specification of Letters Patent.

Patented Sept. 24, 1907.

Application filed June 23, 1906. Serial No. 323,009.

To all whom it may concern:

Be it known that I, ROBERT CHARLES COLE, a citizen of the United States, residing in Hartford, county of Hartford, and State of Connecticut, (whose post office address is the same,) have invented certain new and useful Improvements in the Manufacture of Inclosed Fuses, of which the following is a full, true, and concise specification.

The present invention relates to the manufacture of inclosed fuses which have auxiliary wires associated with their inclosing cases for indicating the condition of the main fuse link or other purpose; and the invention consists in the improved and economical method of making such fuses and in the construction of the same, as will be presently described and more particularly pointed out in the accompanying claims.

Inclosed or cartridge fuses of modern construction consist of a tubular case which contains the main fuse link and is closed at its ends by metallic caps or ferrules, which latter are electrically connected to the ends of the link, and constitute, directly or indirectly, the electrical contact terminals of the device. The auxiliary or indicating wire is connected to the terminals in parallel or shunt relation to the main fuse link and is usually associated in some way with the wall of the tubular case so that when the main fuse is ruptured by the current a change is effected in the external appearance of the device. A filling of some refractory and comminuted material, capable of dissipating the heat and gases attendant upon the rupture of the main link, is also packed into the case around the link before the end terminals are affixed. The present invention relates more especially to the manner of connecting the said auxiliary or indicating wire with the terminals of the main fuse, so that its electrical contact therewith will be permanent and secure, and whereby the necessity of soldering the same to the fuse link or its terminals may be avoided without risk of subsequent disconnection and consequent failure of operation, and whereby also the partially completed fuse tubes may be stored and handled without injury.

In the accompanying drawings, Figures 1 to 4 illustrate the successive steps in the manufacture of an inclosed fuse according to my invention and Fig. 4 represents an inclosed fuse embodying my invention with one end shown in longitudinal section.

In the practice of the invention, the fine wire A is first threaded into or otherwise associated with the fuse tube or case B so that a certain portion of it occupies a predetermined position with respect to the wall of the tube. In the case illustrated, the central part of the wire is located at the exterior of the fuse tube and the ends pass through fine holes into the interior and from thence project toward or out of the open ends of the tube. The projecting ends of this fine wire are

then pushed or drawn through suitable openings C, previously made in the casing, as indicated by Fig. 2, and metallic holders D, which may conveniently be ordinary unlacquered copper eyelets, are then pushed into the said apertures C and clenched therein so as to bind each end of the fine wire firmly between the wall of the opening and the body of the eyelet. By this means the fine indicator wire, which has considerable temper or resiliency, is securely and positively fastened to the ends of the fuse case so that it cannot spring back within the same or otherwise become displaced, and is maintained in good electrical connection with a contact member, i. e. the head of the holder, located on the exterior of the tube. The invention, however, is not limited to this particular method of fastening, and metallic holders of other forms than the eyelet herein shown may be employed with equal effect provided they have secure electrical contact with the fine wire.

The setting of the eyelet may be done by hand or by any ordinary punching mechanism, but I prefer a means which will leave the head or flange of the eyelet slanted toward the end of the case as indicated by Fig. 3, so that the end cap H may be readily pushed over it as will be presently described. When the indicator wire has its central part located on the outside of the fuse tube, as in the present illustration, a protecting paster E, represented by the black line in Fig. 3, is placed over the exposed portion for the purpose of protecting the same and the fuse tube and attached wire may then be stored or transported, even with considerable roughness in handling, without in any way injuring the fine wire or affecting its connections, which, as previously described, are rendered permanent by the upsetting of the eyelets.

In completing the device, the main fuse link F and the filling G are inserted into the tube and the ferrules H are pushed over the heads of the holders and secured in place by means of the screws H' in ordinary manner. The ferrules in encountering the inclined heads, which are of comparatively soft metal and in riding over the same, wear for themselves clean-wiped contact surfaces with said heads, whereby the said ferrules are brought into good electrical connection with the ends of the indicator wire.

In Fig. 4 of the drawing the relation of the ferrule and head of holder is somewhat exaggerated for illustration, but it will be understood that the ferrule fits snugly upon the end of the fuse case notwithstanding the interposed head of the holder. The presence of the said holder in addition serves to aid in retaining the ferrule in position.

In the device as shown in Figs. 3 and 4, an outside label J covers the paster E and is properly arranged with respect to the same and to the wire so that it be-

comes charred or discolored when the indicator wire becomes heated or fused, but the arrangement of the label or of other means for producing an indication by the heat of the indicator wire is not material to the 5 present invention.

Having described my invention what I claim and desire to secure by United States Letters Patent is the following:

1. An inclosed fuse comprising an inclosing case, an 10 indicator wire associated with said case, a metallic holder fastening the end of said wire to the wall of the case and an end closure for the case covering said metallic holder.
2. As a means for securing the indicator wires of inclosed fuses, the combination with the casing having an 15 opening therein, of an eyelet inserted in said opening and upset or pressed against the end portion of the wire.
3. An inclosed fuse comprising an inclosing case having an indicator wire associated therewith, metallic holders fastening the ends of said wire to the wall of the case, 20 ferrules closing the ends of the case and means independent of said holders for securing said ferrules in place.

4. An inclosed fuse comprising an inclosing case, an indicator wire with its ends located in openings in the wall of said case, metallic holders in said openings in contact with said ends and ferrules on the ends of the case in 25 contact with said holders.

5. An inclosed fuse comprising an inclosing case, an indicator wire associated therewith, and an inclined contact member located on said case in electrical contact with said wire, in combination with a metallic contact terminal fitting the end of said case and adapted to ride over 30 said inclined member.

6. An inclosed fuse comprising an inclosing case and terminal contacts thereon, an indicator wire associated with said case and a metallic holder fastening the end 35 of said wire to the wall of the case independently of said terminal contacts.

In testimony whereof, I have signed my name to the specification in the presence of two subscribing witnesses.

ROBERT CHARLES COLE.
